S. AKIMOV

WINDOW WASHER'S SEAT

Filed June 21, 1927

FIG.

FIG. 3.

FIG. 4.

INVENTOR.
SAM AKIMOV.
BY Graves Griffith.

ATTORNEY .

UNITED STATES PATENT OFFICE.

SAM AKIMOV, OF OAKLAND, CALIFORNIA.

WINDOW-WASHER'S SEAT.

Application filed June 21, 1927. Serial No. 200,837.

This invention relates to improvements in safety appliances and more particularly to safety seats, or platforms, for window washers. The present invention consists of a suitable platform or seat having sill-clamping means, so arranged relative to the platform that said platform, or seat, may be placed upon the ledge of any window and its clamp means readily adjusted to the window sill to clamp the platform in position in the window frame to provide a safe means upon which the window washer may stand, or be seated, during the time he is washing the windows or the outside of the building.

Various safety appliances have been provided for the security of window washers, but none of these, to my knowledge have utilized the principles involved in my present construction.

The primary object of my invention is to provide a safe, strong, and reliable seat, or platform, of the character designated that may be easily and quickly placed on any window ledge and clamped thereto to provide a safe seat, or platform, for the use of window washers in washing the outside windows of buildings.

Another object of the invention is to provide a seat of the class designated that embodies in its construction a simple and readily adjustable clamping means adapting it to be rigidly clamped in position to the sill of a window.

Other objects and advantages of my invention will be apparent with reference to the subjoined specification and accompanying one sheet of drawings in which:

Figure 1 is a plan view of my improved window washer's seat, showing the preferred construction embodying the principles of my invention;

Figure 2 is a side elevation of the seat, showing it mounted upon the ledge of a window, with its clamp means adjusted to the sill thereof;

Figure 3 is a front elevation partly in section, the section being indicated by the line 3-3, in Figure 1; and

Figure 4 is an enlarged sectional detail of one of the clamps and its adjusting screw, the section being indicated by the line 4-4, in Figure 1.

Referring more specifically to the draw-

ings, the frame 5 preferably consists of a rectangular piece of wood, having provided on its under surface a pair of spaced angle-iron braces 6 and 6' bolted thereto by a plurality of bolts 7 and 7'.

A pair of supports 8 and 8' are disposed edgewise under the frame or platform 5, and abut against the inner faces of the braces 6 and 6', with stiffening bars 9 and 9' disposed against the inner faces of said supports 8 and 8', said braces 6 and 6' and bars 9 and 9', embracing the said supports 8 and 8', the several parts being rigidly bolted together by rows of bolts 10 and 10'.

The braces 6 and 6' extend slightly beyond the front edge of the platform 5 and embrace a transverse clamp-supporting member 11, the member 11 being provided with depending lugs 12 and 12' adapted to fit between the extremities of the braces 6 and 6' and the bars 9 and 9' to which said lugs 12' are rigidly bolted.

A pair of bosses 13 and 13' are integrally formed with the clamp-supporting member and are positioned immediately adjacent the lugs 12 and 12' thereof, said bosses being provided with tapped openings 14 and 14' adapted to receive the adjusting screws 15 and 15', as hereinafter described.

The front ends of the supports 8 and 8' are of considerably less depth than the rear ends, as clearly shown in Figure 2, the under forward edges thereof 16 and 16' being bevelled or tapered rearwardly throughout more than half their lengths, so that said supports will rest upon and adapt themselves to the slant of any ordinary window sash, as indicated by the dot-and-dash lines in Figure 2.

When the seat, or platform, 5 is positioned upon the window sash, as shown in Figure 2, the upper face thereof is substantially level and the window washer may sit or stand thereon while washing the outside of the windows.

The seat is held in place by means of a pair of threaded adjusting screws 15 and 15' 100 which are held by the tapped openings 14 and 14' formed in the bosses 13 and 13', these adjusting screws being provided at their free ends with bearing sections 17 and 17' and integrally formed heads 18 and 18', 105 through which loosely mounted handles 19 and 19' extend.

Sill-engaging hooks, or clamps, 20 and 20'

are mounted upon the bearing sections 17 and 17' of the adjusting screws, and consist of bosses 21 and 21' having openings 22 and 22' adapted to loosely fit the sections 17 and 17' of the adjusting screws' shank sections 22, and inwardly projecting lugs 24 and 24' adapted to engage under the window sill as clearly shown in Figure 2.

It is obvious that when the seat is placed 10 upon the window sash, as shown in Figure 2, with the sill engaging hooks 20 and 20' engaging the sill, and the handles 19 and 19' are rotated, the hooks 20 and 20' will clamp 15 the sill and draw the platform upwardly toward the rear edge thereof until the front end of the platform is wedged tightly thereagainst, from which position it will be impossible to accidentally dislodge the platform from the sash. The window washer 20 may be seated upon the platform in the position ordinarily assumed when sitting upon the sash, with his limbs extending into the room, or he may stand upon the platform and work in standing position, with a much

greater degree of safety than is possible with 25 the usual make-shift appliances.

Having thus described my invention, I claim and desire to secure by Letters Patent:

In a window washer's seat comprising a 30 rectangular frame consisting of a seat portion, a pair of spaced supports mounted under said seat portion and having their lower edges bevelled at an angular inclination relative to said seat portion, spaced 35 bosses carried by said frame, adjusting screws mounted in said bosses and projecting outwardly from the frame and having heads formed at their outer ends providing shoulders, means carried by the outer ends 40 of said screws for causing their adjustment in said bosses, and loosely mounted clamp members carried by said screws and abutting against said shoulders and adapted for adjustment relative to said frame. 45

In testimony whereof I have affixed my signature.

SAM AKIMOV.
